DESIGN FOR A STOCKING

Hans Thierfelder, Auerbach in Erzgebirge,
Germany

Application December 29, 1938, Serial No. 82,031
In Germany April 6 and 24, 1938

Term of patent 3½ years

To all whom it may concern:

Be it known that I, Hans Thierfelder, a citizen of the German Reich, residing at Auerbach in Erzgebirge, Germany, have invented a new, original, and ornamental Design for Stockings, of which the following is a specification, reference being had to the accompanying drawing, forming part thereof.

Figure 1 is a side view of a stocking, showing my new design, and

Figure 2 is a fragmentary portion of the rear view of the stocking, a part being broken away for convenience of illustration.

The characteristic feature of the design consists of a pair of arched lines composed of star-like elements 1 interspaced by dots which extend on each side of the back seam 5 of the stocking, the upper portion of the arched lines diverging from the back seam 5 and the lower portion 2 extending substantially parallel to the seam 5 and terminating a substantial distance from the heel portion 6.

I claim:

The ornamental design for a stocking, as shown and described.

HANS THIERFELDER.
